CLAIM

The ornamental design for a gun safe, as shown and described.

DESCRIPTION

FIG. 1 is a top perspective view of a gun safe, showing our new design, in a closed configuration;

FIG. 2 is a bottom perspective view of FIG. 1;

FIG. 3 is a front elevational view of FIG. 1;

FIG. 4 is a rear elevational view of FIG. 1;

FIG. 5 is a left side elevational view of FIG. 1, the right side elevational view being a mirror image thereof;

FIG. 6 is a top plan view of FIG. 1;

FIG. 7 is a bottom plan view of FIG. 1;

FIG. 8 is another top perspective view of FIG. 1 shown in an open configuration;

FIG. 9 is a front elevational view of FIG. 8;

FIG. 10 is a rear elevational view of FIG. 8;

FIG. 11 is a left side elevational view of FIG. 8, the right side elevational view being a mirror image thereof;

FIG. 12 is a top plan view of FIG. 8; and,

FIG. 13 is a bottom plan view of FIG. 8.

The broken lines in the figures depict portions of the gun safe that form no part of the claimed design.
